US00D819604S

(12) **United States Design Patent** (10) **Patent No.:** **US D819,604 S**
(45) **Date of Patent:** **** Jun. 5, 2018**

(54) **EARBUD CONNECTOR PLATE**

(71) Applicant: **Oculus VR, LLC**, Menlo Park, CA (US)

(72) Inventors: **Peter Wesley Bristol**, Seattle, WA (US); **Quintin Morris**, Issaquah, WA (US); **James Stocker Webb**, Seattle, WA (US); **Mark Shintaro Ando**, Seattle, WA (US); **David Tao**, Santa Clara, CA (US); **Daniel James Faulkner**, Menlo Park, CA (US)

(73) Assignee: **Oculus VR, LLC**, Menlo Park, CA (US)

(**) Term: **15 Years**

(21) Appl. No.: **29/595,131**

(22) Filed: **Feb. 24, 2017**

Related U.S. Application Data

(63) Continuation of application No. 29/550,170, filed on Dec. 30, 2015, now Pat. No. Des. 783,576.

(57) **CLAIM**

The ornamental design for an earbud connector plate, as shown and described.

DESCRIPTION

FIG. 1 is a front isometric view of an earbud connector plate showing the new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a front isometric view of another embodiment of an earbud connector plate showing the new design.

FIG. 9 is a front elevation view thereof.

FIG. 10 is a rear elevation view thereof.

FIG. 11 is a left side elevation view thereof.

FIG. 12 is a right side elevation view thereof.

FIG. 13 is a top plan view thereof; and,

FIG. 14 is a bottom plan view thereof.

1 Claim, 10 Drawing Sheets
